CLAIM

The ornamental design for a goggle component, as shown and described.

DESCRIPTION

FIG. 1 is a front perspective view of the goggle component of the present invention;

FIG. 2 is a right-side elevational view thereof;

FIG. 3 is the left-side elevational view thereof;

FIG. 4 is a front elevational view thereof;

FIG. 5 is a rear elevational view thereof;

FIG. 6 is a top plan view thereof; and,

FIG. 7 is a bottom plan view thereof.

Phantom lining, where utilized, is for illustrative purposes only and forms no part of the claimed design.
